UNITED STATES PATENT OFFICE.

GEORGE K. DAVOL, OF SAN FRANCISCO, CALIFORNIA.

VALVE-GEAR.

1,160,582.

Specification of Letters Patent. Patented Nov. 16, 1915.

Application filed November 12, 1912. Serial No. 730,832.

To all whom it may concern:

Be it known that I, GEORGE K. DAVOL, a citizen of the United States, residing in the city and county of San Francisco, in the State of California, have invented a certain new and useful form of Valve-Gear for Engines, of which the following is a specification.

My invention relates to a form of valve gear designed to have particular application to internal combustion engines.

This form of valve gear which embodies my invention can be applied to many different forms of internal combustion engines and also to steam and other fluid pressure engines, but, as it is designed to have particular application to the two-stroke cycle internal combustion engine, in which fuel is injected into the cylinder at the beginning of the working stroke, I will confine myself in these specifications to describing the gear in this application, although other applications of the valve gear will of course be evident.

In an engine of the class above indicated the usual functions of a valve gear are as follows: 1.—Operation of the fuel valve. 2.—Operation of the scavenging valve or valves. 3.—Operation of the starting valve. 4.—Operation of a compression relief valve, or operating the scavenging valves so as to relieve compression at starting.

The exhaust in an engine of this class usually takes place through ports in the cylinder walls which are overrun by the working piston and therefore the valve gear is not ordinarily called upon to operate exhaust valves. In an engine of the class referred to, air is compressed in the cylinder by the inward stroke of the piston and at or near the point of highest compression the fuel valve is opened and fuel injected into the cylinder, after which the working stroke follows. Shortly after the exhaust ports are uncovered by the piston, the scavenging valves are opened and scavenging air forced into or through the cylinder, displacing the products of combustion. The compression stroke then follows. For starting, the fuel valve is ordinarily thrown out of gear and the engine operated by compressed air until it attains a suitable speed, when the compressed air is discontinued and the fuel valve thrown into gear. When operating on compressed air it is advantageous that the degree of compression of the air in the

working cylinder be moderated, or, in other words, the compression relieved. This may be accomplished by holding open the scavenging valves for the whole or a portion of what, in full running gear, constitutes the compression stroke. These various functions can be accomplished if the mid-point of the opening and closing of the fuel valve be at 180 degrees from the mid-point of the opening and closing of the scavenging valves, and when starting on compressed air, if the mid-point of the opening and closing of the starting air valve be at 180 degrees from the mid-point of the opening and closing of the scavenging valves, the 180 degrees being referred of course to the revolution of the main crank of engine. When running on compressed air at starting, it is usually desirable, however, that the air valve be opened for a longer period than that which embraces the opening of the fuel valve when running on fuel, also when starting it is desirable that the scavenging valves be held open longer than when running on fuel, in order to relieve the compression on the cylinder, as above-mentioned. For reversing the engine and for starting, it is necessary that the points of opening and closing the fuel valve, scavenging valve and starting air valve be varied with reference to the crank of the engine. It is also desirable that the angular position of the points of the opening and closing of the fuel valve be susceptible of variation when running on fuel. In addition, therefore, to the four operating functions hereinbefore listed, the valve gear is called upon to afford a means of varying the angular position with reference to the crank pin of the engine of the points of opening and closing the fuel valve, scavenging valve, and starting air valve.

In the accompanying drawings: Figures 1, 2, 3, 4 and 5 show diagrammatically an elementary form of the valve gear with the parts in different positions of movement. Figs. 6 and 7 show diagrammatically a further developed form of the valve gear showing its application to a two-cylinder engine having cranks set at 180 degrees. The two Figs. 6 and 7, showing the gear in differently set positions. Fig. 8 shows a plan view of the valve gear as it is applied to a two-cylinder engine having cranks at 180 degrees. Fig. 9 shows a front view of the same gear as shown in Fig. 8, having for clear,

ness the scavenging valve rollers and brackets removed. Fig. 10 shows an enlarged side view of one of the scavenging valve rollers and bracket shown in plan view in Fig. 8. Fig. 11 shows a central longitudinal section through the axis of the valve gear yoke and guiding frame, taken on the line X-X, Fig. 8. Fig. 12 shows a similar section taken at right angles to the section shown in Fig. 11 and taken on the line Y-Y, Fig. 8.

The same parts are designated by the same reference numbers in all the drawings.

Referring to Fig. 1 which represents diagrammatically an elementary form of the gear, the crank shaft of the engine may be represented at 1, the line O-O representing a continuation of the center line of the working cylinder, and the arrow 2, indicates the direction of the outward or working stroke of the piston. The crank pin 3, is in the same angular position as the main working crank of the engine to which the working piston is connected. When the crank pin 3, is at the point "0", the working crank is on its outer dead center.

The pin 3, is connected by the link 4, to the pin 5, carried by the sliding block 6, which reciprocates on the guides 7. The pin 5, is also connected by the link 8, to the pin 9, which is carried by the reciprocating cam block 10. This cam block reciprocates on the guide 11, by which it is confined to a straight line movement.

The cam block has the cam 12, formed on it and bearing against the surface of the block 10, and cam 12, are the rollers 13 and 14. These rollers must be assumed to be confined by any suitable means to movements in the line 15 and 16. The roller 13, represents the fuel valve roller or the roller movements of which, in the direction of the arrow 17, opens the fuel valve. The roller 14, represents the scavenging valve roller or the roller the movement of which, in the direction of the arrow 17, opens the scavenging valve.

In the position of the parts shown in Fig. 1, neither of the rollers 13 or 14, are in contact with the cam 12, and both fuel valve and scavenging valve are closed. If the pin 3, and the connecting parts move to the positions as shown in Fig. 2, the block and cam reach one end of their travel, and the fuel roller 13, is raised, which opens the fuel valve. In Fig. 3 is shown the relative position of the cam and rollers at the opposite end of the cam block travel or when the pin 3, has reached the point at 180 degrees from the position shown in Fig. 2, the scavenging valve roller 14, is then raised and the scavenging valve consequently open, while the fuel valve is closed.

Assuming in Figs. 1, 2 and 3 the crank shaft to be revolving in the direction of the

arrow 18, when it will be seen that with the setting of the gear shown in Figs. 1, 2 and 3, the center of the open period of the fuel valve occurs a short interval after the engine crank pin passes its inner dead center, and likewise the center of the open period of the scavenging valve occurs an interval after the engine crank pin passes its outer center.

Now the guides 7, the center line of which is indicated by the line A-A, are movable about the shaft 1 as center, and it will be seen that if they are shifted slightly from the positions shown in Fig. 1, the angular lead which the engine crank pin has over the fuel valve and scavenging valve openings will be varied. Also it is seen that if the engine crank shaft is revolving in a direction opposite to that indicated by the arrow, 18, then to preserve the lead of the engine crank pin over the fuel and scavenging valve openings, the guides 7, should be moved to the positions indicated by the line B-B, Fig. 1. In this way by changing the angular position of the guides 7, about the center 1, the gear can be set for running the engine in either direction. Any angular movement of the guides will also not only have the effect of changing the angular lead or follow of the engine crank pin with reference to the opening and closing of the valves, but such change in the angular position of the guides will also affect the extent of travel of the cam block 10, and cam 12, and vary the relation of such range of travel to the rollers 13 and 14. This is an important feature of the gear. To clearly demonstrate this, in Fig. 4, I show the guides moved to the angular position indicated by the line C-C. As here shown the pin 3, is on the center line of the guides and all the parts are at one end of their travel. It is seen that in the range of travel given to the cam 12, when the gear is in this position, the cam 12, will not come in contact with the roller 13, at all, and so in this position of the guides 7, the fuel valve is "thrown out of gear" or not operated.

In Fig. 5, I show the relative position of the cam and rollers when the pin 3, has reached the point at 180 degrees from the position shown in Fig. 4, with the guides 7, in the same angular position as shown in Fig. 4. The scavenging valve roller is where shown raised and it can be readily seen that for this angular setting of the guides 7, the scavenging valve is opened for a longer period than with the guide setting shown in Figs. 1, 2 and 3. It can now be understood that the angular positions of the guides 7, indicated by the line A-A, Fig. 1, represents a setting suitable for running the engine on fuel in the direction of the arrow, 18, as with this setting of the gear, 120

both fuel and scavenging valves are operated, and the engine crank pin has a lead over the center of the period of the opening of both fuel and scavenging valves. 5 Also it can be seen that the angular setting of the guides, indicated by the line B—B, Fig. 1, represents a setting for running the engine on fuel in a direction opposite to that indicated by the arrow 18. It will similarly 10 be understood that the angular position of the guides, shown in Fig. 4, represents a setting suitable for starting the engine in the direction of the arrow 18, as with this setting, the fuel valve is not operated at all 15 and the scavenging valve is held open for a considerably greater period during the return of inward stroke of the working piston, giving the desired relief to the compression in the cylinder. The starting air valve, 20 as hereinbefore stated, should have the center of its period of opening, at 180 degrees from the center of the scavenging valve opening; so when all parts are in the 25 positions shown in Fig. 4, the starting valve should be at the center of its period of opening. The manner of operating the starting air valve will be explained later. Also it can now be understood without 30 further explanation that the angular position indicated by the line D—D, in Fig. 4, represents the setting of the gear for starting the engine in the direction opposite to that indicated by the arrow 18.

It is seen that the setting given the gear 35 for starting provides for a greater lead of the engine crank pin over the scavenging valve opening and at the same time prolongs the period of opening of the scavenging valve. The effect of this is to keep the 40 scavenging valve open during as much of the return stroke of the piston as may be desired, while at the same time avoiding opening the scavenging valve too early.

In Figs. 6 and 7, I show diagrammatically 45 a further development of the gear and the application to a two-cylinder engine having working cranks at 180 degrees. In Figs. 6 and 7, the engine crank shaft, or a shaft revolving with the crank shaft of the engine 50 is shown at 1. A pin 3, is carried by a crank, mounted on the shaft 1, and carries a sliding block 19, which slides in the yoke 20, which yoke in turn is carried in a frame 21, in which it is free to reciprocate in the 55 direction of the center line E—E. This pin 3, has the same angular relation to the center line X—X, as one of the working crank pins of the engine has to the center line of its cylinder. The frame 21, is movable about 60 the shaft 1, as a center and can be held in any desired angular position. On the center line E—E of the yoke, which center line intersects the axis of the shaft 1, are mounted two pins 22 and 23, one pin at each end 65 of the yoke. Two links 24 and 25, connect

the pins 22 and 23, to the pins 26 and 27, respectively, which pins 26 and 27 are carried by the oscillating cams 28 and 29, respectively, which cams oscillate on the centers 30 and 31. Each of the cams 28 and 29, 70 is intended to operate the fuel and scavenging valves of one of the cylinders of the engine. As the cylinders have cranks at 180 degrees and the movements given these cams by the mechanism already described 75 are exactly opposite, or out of phase 180 degrees, the fuel and scavenging valves will be correctly operated. The cams 28 and 29 correspond to the sliding block and cam 10 and 12 in Fig. 1, and the whole mechanism 80 shown in Figs. 6 and 7, is the practical mechanical equivalent of that shown in Fig. 1, with certain additions. On the fixed centers 32 and 33, are pivoted arms carrying the fuel valve rollers 34 and 35, and arms 85 carrying the scavenging valve rollers 36 and 37. These rollers rest against the faces of the cams 28 and 29, and by their movements away from the cam centers, open the fuel and scavenging valves, through suitable connections. 90

In the positions of all parts shown in Fig. 6, the cam 28 has lifted the roller 34, and the fuel valve of the corresponding cylinder of the engine is therefore open. The cam 29 has lifted the roller 37, and the scavenging valve of the corresponding or opposite cylinder of the engine is therefore open. The starting air valve of each of the cylinders is operated by the rollers 38 and 100 39, which are carried by levers pivoted on the fixed centers 96 and 97. In this arrangement the roller 39, acted on by the cam 29, operates the starting valve of the opposite cylinder, or the cylinder the fuel and 105 scavenging valves of which are operated by the cam 28, and likewise the roller 38, operates the starting valve of the cylinder which has its fuel and scavenging valves operated by the cam 29. 110

It will be seen that in the angular position of the frame 21, as shown in Fig. 6, neither of the rollers 38 and 39, will be acted on by the cams 28 and 29. The cams are therefore shown in extreme position of oscillation for that angular setting of the gear, and the projection on the cam 29 does not then quite reach the roller 39. The angular setting of the gear, shown in Fig. 6, is therefore running on fuel, the fuel and scavenging valves 115 being properly operated while the starting air valve is cut out of gear, or inoperative. 120

In Fig. 7, the frame 21, is shifted to a new angular position, and all parts are shown at one of their extreme positions of travel. It will be seen that in this angular setting of the gear the fuel rollers 34 and 35, will not be lifted at all by the cams 28 and 29, and the fuel valves are therefore cut out 125 of gear or inoperative. The scavenging valves 130

have a longer period of opening and the rollers 38 and 39, are, in this angular setting of the gear, acted on by the cams 28 and 29, which cams are now pulled farther around on their centers of oscillation and given a shorter range of oscillation.

In the position of all parts shown in Fig. 7, it will be seen that starting air valve roller 39, and scavenging valve roller 37, are both lifted at the same time by the one cam 29, but as the roller 39, operates the starting air valve of the opposite cylinder or the cylinder whose crank is at 180 degrees to the crank of the cylinder whose scavenge valve is 15 opened by the roller 37, the proper action and relation is preserved.

It can now be seen comprehensively, that the gear provides a means of varying the angular lead and follow of all valve operations 20 with reference to the engine crank, varies the duration of the open period of the scavenge valve to suit different angular positions, and also automatically renders the fuel and starting air valve inoperative outside of that range of angular relation to the engine crank which is suitable for their operation.

In Fig. 6, the line F—F represents an angular setting of the gear for running in the 30 opposite direction to that for which the gear is shown set, and likewise in Fig. 7, the line G—G represents the angular setting of the gear for starting the engine in the opposite direction. It will be understood that 35 a considerable range in the angular setting of the gear for either running on fuel or for starting is allowable.

In Fig. 8, I show a plan view of the gear as actually applied to a two-cylinder internal combustion engine; the engine having working cranks set at 180 degrees. Fig. 8 shows the ends of the cylinders 40 and 41, of the engine which, for simplicity of description, I will assume to be a vertical engine. Fig. 9 shows the front view of the same arrangement of gear as is shown in plan in Fig. 8. In Fig. 9 I show one side of the cam ring 43, and the adjoining portion of the cylinder 41, in section; and in Fig. 9, 50 all the scavenge valves, scavenge valve rollers and supports and the starting air valve cams are, for simplicity, removed.

Referring to Figs. 8 and 9, the two ends of the cylinders 40 and 41, have four scavenge valves set in each, designated by the numbers 44, 45, 46, 47, 48, 49, 50 and 51, and arranged symmetrically about the centers of the cylinders. The fuel valves 52 and 53 are set in the center of each of the cylinders, and the starting air valves 54 and 55 are set at one side in the head of each cylinder. The valve gear operating shaft 56, Fig. 9, is driven by any suitable means to revolve evenly with the crank shaft of engine and 65 this shaft carries at its upper end the crank

and pin 57, Fig. 8. In Figs. 11 and 12, I show in two cross sections taken on lines X—X and Y—Y, respectively, in Fig. 8, the arrangement of the parts now described and which are shown in plan in Fig. 8. The pin, 57, carries a sliding block 58, which slides in the yoke 59. This yoke is guided to reciprocate in a slide formed in the cover 60 of the circular gear box 61. In Fig. 8, the cover 60 is removed in order to show the yoke and other parts beneath it, but it is shown in place clearly in Figs. 9, 11 and 12. The yoke 59 carries the pins 62 and 63, which are connected by the links 64 and 65 to the pins 66 and 67 in the oscillating cam rings 42 and 43. These cam rings I show made in two parts, secured together as shown in the sectional part of the Fig. 9, an upper part on which the cams for operating the scavenge valves are formed and a lower supporting 85 part which rests on the ledge found on the cylinders. These cam rings, it is seen, encircle all that portion of the cylinder heads in which the scavenge, fuel, and starting air valves are placed. On the upper portion of 90 each of the cam rings 42 and 43, are formed four cams for operating the scavenge valves, which cams at one end of the oscillation of the rings act on the scavenge valve rollers 68, 69, 70, 71, 72, 73, 74 and 75. The roller 68 is shown held in place by a lever 76, and bracket 77, but the levers and brackets of all the other scavenge valve rollers are, for simplicity, removed. These rollers 69 to 75, inclusive, the means of support or attachment 95 of which are not shown, it will be understood are constrained to move as is the roller 68, in planes passing through the axis of their respective valves. The detail of these levers and brackets and the manner in which the movement of the rollers is transmitted to the scavenge valves is shown in Fig. 10. As there shown, the lever 76, is pivoted on the pin 78, which is carried by the bracket 77, which bracket is secured to the cylinder head. The roller 68, is carried by one end of the lever 76 and bears against the cam ring 42, while the other end of the lever carries a set screw 79, which acts on the end of the stem of the scavenge valve 44. The fuel valves 52 and 53, in the center of the cylinders 40 and 41, are operated from the cam rings by means of the oscillating arms 80 and 81, which are in sliding engagement at 100 their outer ends with the pins 98 and 99, which are fixed in the cam rings 42 and 43. The mechanism by which the movement of these arms is made to open and close the fuel valves at one end of the swing or oscillation of the arms is immaterial. I have shown, however, the fixed bodies of the fuel valves to have cut on them, steep pitch screw threads and on these threads the sleeves 82 and 83 turn. These sleeves are formed integral with the arms 80 and 81 and the yokes 110 115 120 125 130

84 and 85. At one end of their movement or oscillation, embracing the highest portion of their movement, the yokes come in contact with the nuts 86 and 87 on the stems of the valves and so raise and open the fuel valves, which are closed by suitable springs as the sleeves move downward again. Thus it is seen that at one end of the oscillation of the cam rings the four cams formed on each of the rings come in contact with the scavenge valve rollers forcing them outwardly from the cylinders and as shown in Fig. 10, causing the scavenge valves to be opened, while at the opposite end of the oscillation of the cam rings, the fuel valves are opened by the connections described.

With the setting of the gear shown in Figs. 8 and 9, the starting air valves 54 and 55 are not operated at all, as the setting shown is for running on fuel. The two starting air valves 54 and 55, are operated by the single rocking lever 88, which is pivoted on the central pin 89, suitably carried by the cylinders or frame of the engine.

25 The two opposite ends of the lever 88, carry set screws which are adjusted to just clear the end of the stems of the starting valves. The two opposite sides of the lever 88, also carry rollers 90 and 91.

30 On the lower portion of the cam rings 42 and 43, are secured two cams 92 and 93, which are shown in plan in Fig. 8, but which are removed in Fig. 9, and which with the setting of the gear shown in Fig. 8 do not act upon anything. When, however, the gear box 61, is turned to the proper angular position for starting the engine, the cam rings 42 and 43 are given a different range of oscillation and the cams 92 and 93 then

40 come in contact with the rollers 90 and 91 respectively. It is seen that if the cam ring 42 be oscillated far enough in the direction of the arrow 94, the cam 92, will act against the under side of the roller 90, raise that end of the lever 88 and cause to be pushed down the stem of the starting air valve 55. Similarly the cam 93 will operate the valve 54. The gear box 61, is carried by the bracket 95, Fig. 9, which is part of the cylinders or frame of the engine.

45 As is shown in the sectional views, Figs. 11 and 12, the gear box may be turned in this support and may be set to any angular position desired.

50 The means of turning the gear box and of holding it in the position desired, I have not indicated as any suitable means may be employed.

55 It is now seen that the design of the valve gear shown in Figs. 8 to 12, performs all the functions hereinbefore indicated and shown diagrammatically in Figs. 6 and 7. Thus, in the setting shown in Figs. 8 and 9, the scavenge valves and fuel valves are operated at opposite points of the revolution of the shaft 56, while if the gear box 61 is

turned to the proper angular position giving the proper different range to the oscillation to the cam rings, the fuel valves will not be operated at all, as the arms 80 and 81 will not be swung far enough to raise the yokes 84 and 85 to contact with the nuts 86 and 87 on the valve stems, while in such changed range of oscillation of the cam rings, the cams 92 and 93 will act on the rollers 90 and 91 and so operate the starting valves 54 and 55. Thus while the shifting of the gear box 61, about the shaft 56 as a center, gives the necessary change of angular lead with reference to the engine crank to the operation of the valves for starting on air and for running on fuel, this angular adjustment also serves at the same time by giving to the rings 42 and 43 and an entirely different range and position of movement, to properly throw out and in the operation of the starting air and fuel valves, and to properly vary the duration of the opening of the scavenge valve.

55 It should be noted that the oscillating cam rings, encircling all the scavenge valves, enables a plurality of scavenge valves to be operated in a very simple manner; also that the thrust of the scavenge valve rollers balance each other on the cam ring in the arrangement shown.

90 In connection with the following claims will be understood that, while I have employed terms more or less specific in referring to the structural parts of my invention, I do not limit myself to these parts as herein shown and described but include within said terms any equivalents that will accomplish substantially the same results.

95 What I claim is:

1. In a valve gear, the combination of a revolving shaft, a reciprocating part deriving its reciprocating motion from the said revolving shaft, guides in which the said part reciprocates, the said guides being angularly adjustable about the said shaft as a center, a cam having cyclic motion, and a link connecting the said reciprocating part with the said cam.

2. In a valve gear, the combination of a reciprocating part moving in suitable guides and deriving its reciprocating motion from a revolving shaft, a cam having cyclic motion, a link connecting the said cam to the said reciprocating part, and means for changing the travel of the said cam by varying the angular position of the said guides about the said shaft as center.

3. In a valve gear, the combination of a revolving shaft, a reciprocating part moving in straight guides and deriving its movement from the said revolving shaft, the said guides being arranged with their center line passing through the axis of the said shaft and being angularly movable or adjustable about the axis of the said shaft as a center,

6 a cam or cams having cyclic motion, and a link transmitting motion from the said reciprocating part to the said cam or cams.

4. In a valve gear, the combination of a revolving shaft carrying a crank and crank pin, a reciprocating yoke having a slot or slide at right angles to its direction of reciprocation, the said crank pin engaging in the said slot or slide, a cam having cyclic motion, a link connecting the said cam with the said yoke, and a guide frame in which the said yoke reciprocates, the said guide frame being angularly adjustable about the said shaft as a center.

15 5. In a valve gear for a two cylinder engine, having working cranks set at 180 degrees from each other, the combination of a revolving shaft carrying a crank pin, a reciprocating yoke engaging the said crank pin, two oscillating cams, two links, each one of said links connecting one of the two opposite ends of the said yoke to one of the oscillating cams, a guide frame in which the said yoke reciprocates, the said guide frame being angularly adjustable about the said shaft as a center.

30 6. In a valve gear for a two-cylinder engine, the combination of a revolving shaft, a reciprocating part deriving motion from the said revolving shaft, a guide frame in which the said reciprocating part moves, the said guide frame being angularly adjustable about the said shaft as a center, two oscillating cams, and a link connecting each of the two oscillating cams to a point on the said reciprocating part, which points are on opposite sides of the axis of the said revolving shaft.

45 7. In a valve gear for a two-cylinder engine, the combination of a revolving shaft, a reciprocating yoke deriving motion from the said revolving shaft, the center line of the said yoke intersecting the axis of the said shaft, two oscillating parts, two links connecting the said oscillating parts to points on the center line of the said yoke, the said two points being on opposite sides of the axis of the said shaft, and a guide frame in which the said yoke reciprocates, the said guide frame being angularly adjustable about the axis of the said shaft.

55 8. In a valve gear for a two-cylinder internal combustion engine, the combination of a fuel valve and a starting air valve for each cylinder, a reciprocating part, two oscillating cams deriving motion from the said reciprocating part through suitable connections, and mechanism between the said cams and the said valves whereby each 60 one of the said cams operates the fuel valve of one of the said cylinders and the starting air valve of the other of the said cylinders.

65 9. In a valve gear for a two-cylinder internal combustion engine, the combination of a fuel valve and a starting air valve for

each cylinder, two working cranks set at 180 degrees apart, a reciprocating yoke deriving motion from a shaft, two oscillating cams connected by links to opposite ends of the said reciprocating yoke, a guide frame 70 for said yoke angularly adjustable about the said shaft, and mechanism between the cams and valves through which one of the said cams operates the fuel valve of the first cylinder and the starting air valve of the 75 second cylinder, and the other of said cams operates the fuel valve of the second cylinder and the starting air valve of the first cylinder.

10. In a valve gear for a two-cylinder engine, the combination of a fuel valve and a starting air valve for each cylinder, two parts having cyclic motion, one of the said parts being carried on each of said cylinders and operating the fuel valve of the cylinder 80 on which it is carried, and a single rocking lever having oppositely extending arms and mounted between the said cylinders, each of the arms of said lever operating the starting air valve of one of said cylinders, said 85 rocking lever being actuated by alternate contact with the two said parts.

11. In a valve gear for an engine, the combination of a plurality of valves in the cylinder head of the engine, an oscillating ring carried by the cylinder head and encircling said valves, and valve operating connections between the said ring and the said valves.

12. In a valve gear for an internal combustion engine, the combination of a plurality of scavenging valves in the cylinder head of the engine, an oscillating ring mounted on the cylinder head and encircling said valves, cam projections on the 100 said ring, rollers acted on by the said cam projections, and levers for transmitting the movement of the said rollers to the said valves.

13. In a valve gear for an internal combustion engine, the combination of a scavenging valve or valves and a fuel valve or valves in the cylinder head of the engine, an oscillating ring mounted on the cylinder head and encircling the said valves, and connections between the said valves and the said ring, the said connections transmitting motion from the said ring to the said scavenging valves to open the said scavenging valves at one end of the oscillation of the said ring 110 and transmitting motion from the said ring to the said fuel valves to open the said valves at the opposite end of the oscillation of the said ring.

14. In a valve gear for an internal combustion engine, the combination of valves in the cylinder head of the engine, an oscillating ring mounted on the cylinder head and encircling the said valves having its axis of oscillation coinciding with or par- 125

allel to the axis of the cylinder, and levers mounted to transmit motion from said ring to said valves to operate the same.

15. In a valve gear for an engine, the combination of valves in the cylinder head of the engine, a reciprocating yoke deriving motion from a shaft, an oscillating ring mounted on the cylinder head and encircling said valves, a link connecting the said ring to said yoke, a frame guiding said yoke and angularly adjustable about the said shaft, and mechanism for transmitting motion from the said ring to the said valves.

16. In a valve gear for a two-cylinder internal combustion engine, the combination of fuel valves and starting air valves in the

cylinder heads of the engine, an oscillating ring mounted on each of the cylinder heads and encircling its valves, and connections for transmitting motion from each of the 20 said rings to the fuel valve of one of the cylinders and for transmitting motion from the same ring to the starting air valve of the other of the said two cylinders.

In witness whereof, I hereunto subscribe 25 my name this 2nd day of November A. D., 1912.

GEORGE K. DAVOL
